3 Claims. (Cl. 179—115.5)

Our present invention relates to acoustic instruments of the moving conductor type, as for example electro-dynamic loudspeakers.

It is an object of the present invention to provide a robust construction of moving coil for these instruments, particularly for those which are large in size and adapted to handle considerable amounts of power.

According to the present invention, an acoustic instrument of the moving conductor type comprises in combination with an acoustic diaphragm, or with a skirt carrying an acoustic diaphragm, a moving conductor embedded in a material which does not soften on heating. Preferably, the acoustic diaphragm, or the skirt carrying the acoustic diaphragm, is secured to the moving conductor by the same material as that in which the moving conductor is embedded, and the acoustic diaphragm may comprise a fabric layer embedded in the same material.

The invention is illustrated by way of example in the accompanying drawing in which

Fig. 1 shows a moving conductor according to the invention, mounted for co-operation with a suitable magnet system, and secured to a skirt carrying an acoustic diaphragm, while

Fig. 2 shows a modification of the arrangement shown in Fig. 1.

Referring to Fig. 1, an acoustic current coil 1, for example of insulated aluminum wire, wound on a form 3, is molded under heat and pressure into a mass of material 5 which, after being thus molded, does not soften on further heating, the form 3 acting as the male portion of the mold. Molded to the coil 1 by means of the material 5 is a skirt 7 which carries a suitable acoustic diaphragm, part of which is shown at 9. This skirt 7 may comprise a fabric embedded in the same material which is used in the moving coil at 5, and said same material may be used for securing the diaphragm to the skirt.

The material 5 may be, for example, a resin which polymerizes under heat and pressure. Specifically, we may use a phenol-condensation product such as "Bakelite". This material has the well-known property of being permanent after it is cured, that is, baked under heat and pressure. It will not, subsequently, soften under heat and it is impervious to ordinary solvents.

The ends 11, 13 of the coil 1 are for connection to a suitable source of acoustic frequency, not shown. The coil 1 is mounted in any known or suitable manner for vibration in the air gap 19 between the poles 15, 17 of a pot magnet sys-

tem, as of a dynamic loudspeaker. The coil ends 11 and 13, preferably in the usual form of flexible leads connected to the terminals of the coil 1 may, if desired, be molded in the skirt 7 and brought out at or near the upper edge thereof. In accordance with ordinary practice, it is desirable to bring the leads out of the moving structure at a point thereof sufficiently distant from the pole pieces in order to prevent contact between the leads and the pole pieces. This has heretofore been accomplished by cementing or otherwise securing the leads along the skirt and/or diaphragm.

Although we have illustrated the skirt 7 and the leads 11 and 13 as being within the cone diaphragm 9, it is usually desirable to reverse the positions, placing the skirt 7 and the leads 11 and 13 outside of the end of the cone.

Referring to Fig. 2, a coil 1, wound on a form 3 and molded under heat and pressure into the mass of material 5 which does not soften on subsequent heating, is mounted in any known or suitable manner for vibration between the poles 15, 17 of the pot-magnet system. The coil has molded to it by the same material 5 as that in which the moving conductor 1 is embedded, an acoustic diaphragm, part of which is shown at 9. Preferably, the diaphragm 9 consists of the material 5' molded upon a fabric layer 20.

As above set forth, we have disclosed a method of and means for constructing a moving coil and diaphragm for an electro-dynamic loudspeaker, having the characteristics of rigidity and durability under stringent conditions of moisture, heat, and mechanical stresses. Our improved construction makes possible the use of a large diameter moving coil, of relatively small mass, for high powered speakers that require greater than usual rigidity of the coil form to maintain its circular shape, especially when soft wire is used in the coil.

Because of the unitary and rigid nature of the moving coil and its form, there is no tendency for the individual conductors to vibrate relative to the remaining moving structure. Furthermore, because of the improved construction of the skirt and its unitary relationship with the coil form, and the physical continuity of construction from the coil structure to the diaphragm, large forces are effectively transmitted from the coil to the diaphragm, particularly at the higher audio frequencies, without substantial attenuation. Although we are not prepared to state definitely the reason for attenuation in devices with which we have been familiar, it is believed that lack of prop-

er physical continuity between the moving coil and the diaphragm is a contributing factor.

Having now particularly described and ascertained the nature of our said invention, and in 5 what manner the same is to be performed, we declare that what we claim as new is:

1. In an acoustic instrument of the moving conductor type, a solenoidal conductor and a skirt element, both said conductor and skirt element 10 being embedded in a material which does not soften on heating.

2. In an acoustic device, coil structure constituted by a coil form, a solenoidal conductor about said form, and a skirt element concentric therewith for attaching the coil structure to a diaphragm, the conductor, form, and skirt element

being intimately bonded together by a material that has been polymerized in situ, whereby the device is capable of handling a large power output.

3. In a loud speaker capable of delivering a 80 relatively large amount of power, a solenoidal coil form, a movable conductor on said form, and a frusto-conical skirt element, said coil form, conductor and skirt element being integrally united 85 into a unitary structure by a material that has been polymerized in situ, and a direct acting diaphragm secured to said skirt element by means of the same material.

GEORGE FREDERICK CLARK.
ARTHUR STANLEY RADFORD.
